UNITED STATES PATENT OFFICE.

ELI A. BURT AND HERMEN HARRIS, OF NEW YORK, N. Y.

CLASP FOR HATBANDS.

No. 811,126.

Specification of Letters Patent.

Patented Jan. 30, 1906.

Application filed July 15, 1905. Serial No. 269,867.

To all whom it may concern:

Be it known that we, ELI A. BURT, of New York, Brooklyn, Kings county, New York, and HERMEN HARRIS, of New York, in the county of New York and State of New York, have invented certain new and useful Improvements in Clasps for Hatbands; and we do hereby declare the following to be a full, clear, and exact description of the invention, such as will enable others skilled in the art to which it appertains to make and use the same.

Our invention relates to improved clasps for hatbands, the object of the invention being to provide improvements of this character which can be easily and securely fixed to a band and which when the band is around a hat will be entirely hidden from view; and the invention consists in certain novel features of construction and combinations and arrangements of parts, as will be more fully hereinafter described, and pointed out in the claims.

In the accompanying drawings, Figure 1 is a perspective view illustrating our improvements. Fig. 2 is a view in section, and Fig. 3 is a view showing the clamp detached.

Our improved clasp or clamp comprises two members 1 and 2, and it is the construction of the former with which this application has particular reference.

Member 1 comprises a plate of sheet metal bent longitudinally upon itself at one side of its center, forming a flap 3 and fold 5 and clamping the end of the band between flap 3 and the body of the plate. This flap 3 is much shorter than the body of the plate and leaves an extended single thickness of plate, which we give the reference-numeral 4. This portion or flap 4 is then bent over, tightly clamping the band between flaps 3 and 4, preventing all possibility of the clasp slipping from the end of the band. The folded portion 5 is then bent at an angle into the general shape of a hook, and the band is carried around the hook and secured to the back of the body of member 1 by stitching the lower edge of the band to the plate or in any other approved manner and effectually hiding the clasp member from view.

The member 2 may be formed in various ways, one form being shown in which the member 2 comprises a metal plate folded upon the end of the band and bent into hook form to engage the hook of member 1.

By thus constructing our improvements 55 the band is secured to the clasp against any possibility of slipping and the clasp is entirely hidden from view when the band is in use.

Slight changes might be made in the general form and arrangement of the parts described without departing from our invention, and hence we consider ourselves at liberty to make such changes and alterations as fairly fall within the spirit and scope of our 65 invention.

Having fully described our invention, what we claim as new, and desire to secure by Letters Patent, is—

1. A clamp member for a hatband, comprising a metal plate folded upon itself, the two folds of the plate bent to form a hook and one end portion of the plate bent to overlap the folded portion thereof.

2. A clamp member comprising a metal 75 plate folded upon itself, the two folds of the plate bent to form a hook and one end of the plate bent to overlap the folded portion thereof and a band passing around the folded hook portion and secured to the plate.

3. The combination of a band, a clamp member comprising a metal plate folded upon itself and clamping one end of the band between the folds, said folded portion bent to form a hook, and one end of the plate bent to 85 overlap the folded portion thereof and clamp the band against the same.

4. The combination of a band, a clamp member comprising a plate folded upon itself and clamping one end of the band between the folds, the said folded portion bent to form a hook, the band passing around said hook and over and beyond the folded portion, and the end of the plate bent to overlap the folded portion and clamp the band there- 95 against, said overlapping end of the plate having its free edge in proximity to the hook of the folded portion.

In testimony whereof we have signed this specification in the presence of two subscribing witnesses.

ELI A. BURT.
HERMEN HARRIS.
